EXTRACTION OF PETROLEUM FROM SOLID MATERIALS

Henry Rosenthal, New York, N. Y.

Application August 4, 1934, Serial No. 738,405

8 Claims. (Cl. 196—14)

My invention relates to a novel process for and methods of extraction of oil from oil shale, utilizing as solvent low boiling hydrocarbons, particularly those which are normally gaseous at atmospheric pressures and temperatures. It is particularly related to the extraction of petroleum oil from oil shale in a continuous manner and in a process where solvent is removed from the extract as a part of the petroleum refining, and where the solvent is recovered as a portion of the petroleum refining process.

My invention provides means of recovering petroleum oil from oil shale in a simple and inexpensive manner. Where oil shale is used as a source of petroleum, the liquid product obtained must be refined and fractionated into a number of separate products before the shale oil can be used commercially. Thus, the usual method is to subject the petroleum oil to high temperatures whereby portions of the oil are vaporized and the vapors are recovered after fractionation as gasoline, kerosene, gas oil and similar products. The temperatures to which the crude material is subjected may be either below the point or above the point at which pyrolytic reactions take place prior to the separation of the materials into commercial cuts. As a by-product of the refining operation, there is produced a gas containing hydrocarbon compounds such as propane, butane, pentane, and analogous materials of other series which may be condensed into a liquid under pressure in a number of ways; the usual method being to first absorb these hydrocarbons from the fixed gas with which they are associated, by means of a high boiling petroleum oil. These compounds are then usually removed from the oil menstruum by means of heat and are recovered separately from the fixed gases with which they have been associated. This material is a form of "natural gasoline" and is usually further fractionated to remove small portions of fixed gas as well as of a fraction in which propane is the predominating compound. Frequently in this operation a fraction is also obtained, in which butane is the predominating compound. The principal product of this "stabilizing" is a form of "stabilized natural gasoline" which is a hydrocarbon liquid when maintained under superatmospheric pressure, but which vaporizes at atmospheric pressure. These various "stabilizer" products, that is, the butane cut, the propane cut, or the "stabilized" natural gasoline cut, I use as solvent for removing the shale oil from the rock with which it is associated, or I may use the unstabilized natural

gasoline as it is produced in the vapor recovery portion of the petroleum refining process.

In the extractor proper, the solvent mixes with the oil shale, and during the operation the shale oil is substantially removed, but some of the solvent will remain within the pores of the shale. Where a solvent having a low boiling point is used, separation of the solvent from the shale can easily be accomplished by applying heat to the shale after the oil has been removed. With such low boiling solvent, substantially complete recovery of the solvent from the shale may be effected. This separation of the solvent from the spent shale is accomplished by converting the solvent into the vapor state. By my present invention, these vapors are recovered along with condensable vapors produced in the petroleum refinery, in the vapor recovery section of the refinery.

The objects of my invention, thus, are:

1. To provide novel apparatus for and methods of separating a solvent from the extract in the process of extracting oil from shale.
2. To provide novel means for recovering the solvent vapors removed from the spent shale after extraction.

3. To utilize the lighter fractions of petroleum refining as an extraction medium in the removal of shale oil and to circulate these fractions substantially continuously between the extractor and the petroleum refinery. Other objects of my invention are apparent from these specifications.

My invention may best be described by reference to the accompanying drawing which is a part of this specification. In this drawing

Figure 1 is a diagrammatic layout of one embodiment of my invention.

Figure 2 is an elevation of a preferred form of extractor for use in connection with my invention.

Referring to Figure 1, solvent is contained in tank 1, and is delivered to extractor 2, through the valve 3.

The oil shale is delivered to the crusher 4, where it is reduced to proper size, which I prefer shall be such that the crushed material will fall through a one inch screen and will be retained on a half inch screen. After leaving the crusher the oil shale passes to the screen 5, where it is properly graded and delivered to the conveyor 6, by which it is transferred to the feed hopper 7 of the extractor 2. From the hopper, the crushed oil shale is delivered through rotary valve 8 to the sealed inlet compartment 9 of the extractor, 55

from which it passes through rotary valve 10 to the extraction cylinder 11.

The operations within the extraction cylinder can best be explained by referring to Figure 2.

- 6 The oil shale entering the cylinder from rotary valve 10 is passed into the rotating cylindrical compartment, 12a, by means of the deflector vane 13a. In the rotating cylindrical compartment 12a the shale meets a strong solution about to be 10 discharged from the extraction cylinder 11. The rotation of the compartment 12a carries the shale forward and upward and discharges it into rotating compartment 12b, where the solution strength is somewhat weaker than that in compartment 15 12a. In a similar manner the shale is carried forward until it reaches compartment 12d, into which the fresh solvent is delivered through the valve 3. The shale, leaving compartment 12d and delivered to the compartment 12e by deflector vane 13e, is substantially free from shale oil, but will be wet with solvent besides carrying amounts of solvent by absorption and similar means. In the rotary cylinder 12e the spent shale is drained of its solvent and is passed by means of deflector 20 vane 13f to the compartment 14. The spent shale with its absorbed solvent is passed from the compartment 14 to the conveyor 15. The conveyor 15 is provided with a heating jacket 16, into which suitable heating medium is admitted through the valve 17, and discharged through the outlet 18. While in the conveyor 15 the spent shale is heated sufficiently to completely vaporize its content of absorbed solvent, and it is passed by the conveyor to the rotary valve 19, which discharges the spent 30 shale into the sealed outlet compartment 20 where it is subjected to a vacuum applied through pipe 21. This vacuum acts to eliminate the solvent vapors from the spent shale which is then discharged from the outlet compartment through the rotary valve 22.

The solvent entering through the valve 3 into the rotary compartment 12d, passes in contact with the shale about to be discharged from the extraction cylinder. It is then delivered consecutively to rotating cylinders 12c, 12b, and 12a in counterflow to the movement of the shale, and is then discharged from the extraction cylinder by outlet pipe 23.

Again referring to Figure 1, the spent shale is 50 discharged from rotary valve 22, to conveyor 24, which delivers it to any convenient location.

The solution discharged from the extractor through pipe 23 may be delivered either through valve 25 to the cracking unit 27 or through valve 55 26 to the unit 28. Inasmuch as the cracking and topping units are well known in the art and as any well known type may be used with my invention, neither of these units is shown in detail in the figure, only sufficient detail being shown to 60 fully explain my invention.

The solution passing through valve 25 enters the pump 29 which delivers it to the cracking still 30 where it is subjected to conditions favorable to cause pyrolytic reaction. After passing 65 through the cracking still, the solution is delivered to the reaction chamber 31 and the dephlegmator 32, where a portion is condensed and is recirculated through the cracking still 30 by the pump 34. The vapors from the dephlegmator 32 pass 70 into the rectification portion of the cracking unit as represented by the rectangle 33. This rectangle here represents the various fractionating columns, condensers, storage tanks and other apparatus making up the balance of the cracking 75 unit, including the separator in which the gases

including propane, butane etc. are separated from the liquid components. These gases with their condensable vapors are shown as leaving the cracking unit through the valve 35.

The solution passing through valve 26 is delivered to the tube-still 36 by the pump 37. In the tube-still 36 the solution is heated and delivered to the fractionating column 38 from which as shown a number of side cuts are removed. As shown, a gasoline cut is removed 10 from the top of the column, passed through the condenser 39 and delivered to the separator 40, the gasoline being withdrawn from the bottom of the separator through valve 41 and the vapors and non-condensable gases including propane and 15 butane are withdrawn from the separator through valve 42.

The vapors and gases removed from the cracking unit through the valve 35 and/or removed from the topping unit through the valve 42, are 20 delivered to the vapor recovery unit 43. This may be of any well known type and therefore only sufficient detail is shown to explain the operation in connection with this invention. The rectangle 44 represents the usual absorption unit 25 with the necessary absorbers, compressors, stills, tanks, condensers, etc. The liquid product comprising propane, butane and pentane is withdrawn from the absorption unit through the pipe 45 to the stabilizer or column 46. The fixed gases, 30 dissolved in the liquid which is delivered through pipe 45, are removed through pipe 47. The stabilized gasoline is removed from the bottom of the column and delivered to the tank 48. Propane vapors may be removed through valve 49 or 35 butane vapors through valve 50, and delivered to the condenser 51, in which they are liquefied and from which the liquid is delivered to tank 52. The propane or butane may be delivered to the solvent storage tank 1 by opening valve 53, or the natural gasoline may be delivered to tank 1 by 40 opening valve 54.

The exhauster 55 is connected on its suction side to the sealed inlet compartment 9 and removes therefrom solvent vapors which enter the compartment 9 through the rotary valve 10 and the air which enters the compartment 9 through the rotary valve 8. I prefer that exhauster 55 be so adjusted that the pressure maintained within the sealed inlet compartment 9 be slightly above the pressure of the atmosphere. The 45 exhauster 55 compresses the gases and vapors which it removed from the inlet compartment 9 and delivers them through pipe 56 to the vapor recovery unit 43.

Exhauster 57 is connected on its suction side 55 with the sealed outlet compartment 20. I prefer that exhauster 57 be so adjusted that it maintains within the outlet compartment a pressure of less than half a normal atmosphere. The gases and vapors removed by exhauster 57 from the sealed outlet compartment 20 are compressed and delivered through pipe 56 to the vapor recovery unit 43 where the vapors are recovered along with those entering the recovery unit from 60 the cracking unit and/or the topping unit. 65

Many changes may be made in the details of my invention without departing from the spirit of my invention, and I do not limit myself to the particular forms shown.

Having described my invention so that it may be readily understood by one skilled in the art, I claim:

1. The method of extracting oil-shale which comprises dissolving shale-oil in a hydrocarbon 75

liquid that is gaseous at normal temperatures and pressure by contacting the oil-shale with said hydrocarbon delivered and applied to said oil shale while said hydrocarbon is in the liquid phase, maintaining said hydrocarbon in the liquid phase while in contact with said oil-shale; withdrawing the solution; subjecting the solution, while said solution still contains substantial amounts of the solvent, to the action of heat at such temperature that pyrolytic reactions take place; then separating the solution into fractions, including one fraction of the character of the solvent used; and returning a portion of said fraction to the dissolving step.

2. The method of extracting oil-shale which comprises, dissolving shale-oil in "natural gasoline" by contacting the oil-shale with "natural gasoline" delivered and applied to said oil shale while maintained in liquid phase, maintaining said "natural gasoline" in the liquid phase while in contact with said oil-shale; withdrawing the solution, then subjecting the solution, while it still contains a substantial amount of said solvent, to the action of heat at such temperature that pyrolytic reactions take place; then separating the solution into fractions including one fraction analogous to said "natural gasoline"; and returning a portion of said "latter" fraction to the dissolving step.

3. The method of extracting oil-shale which comprises dissolving shale-oil by contacting said oil-shale with "butane" delivered and applied to said oil shale while maintained in the liquid phase, maintaining said "butane" in the liquid phase while in contact with said oil-shale; withdrawing the solution; then subjecting the solution, while it still contains a substantial amount of butane, to the action of heat at such temperature that pyrolytic reactions take place; then separating the solution into fractions, including one fraction of "butane"; and returning a portion of said "butane" fraction to the dissolving step.

4. The method of extracting oil-shale which comprises dissolving shale-oil by contacting said oil-shale with "propane" delivered and applied to said oil shale while maintained in the liquid phase, maintaining said "propane" in the liquid phase while in contact with said oil-shale; withdrawing the solution; then subjecting the solution, while it still contains a substantial amount of said "propane", to the action of heat at such temperature that pyrolytic reactions take place; then separating the solution into fractions including one fraction of "propane"; and returning a portion of said "propane" fraction to the dissolving step.

5. The method of extracting petroleum bearing solid material which comprises dissolving a portion of the petroleum in a hydrocarbon liquid that is gaseous at normal temperatures and pressure by contacting the petroleum bearing solid material with said hydrocarbon delivered and applied to said petroleum bearing solid material

while said hydrocarbon is in the liquid phase, maintaining said hydrocarbon in the liquid phase while in contact with said petroleum bearing solid material; withdrawing the solution; subjecting the solution, while said solution still contains substantial amounts of the solvent, to the action of heat at such temperature that pyrolytic reactions take place; then separating the solution into fractions, including one fraction of the character of the solvent used; and returning a portion of said fraction to the dissolving step.

6. The method of extracting petroleum bearing solid material which comprises, dissolving a portion of the petroleum in "natural gasoline" by contacting the petroleum bearing solid material with "natural gasoline" delivered and applied to said petroleum bearing solid material while maintained in the liquid phase, maintaining said "natural gasoline" in the liquid phase, while in contact with said petroleum bearing solid material; withdrawing the solution, then subjecting the solution, while it still contains a substantial amount of said solvent, to the action of heat at such temperature that pyrolytic reactions take place; then separating the solution into fractions including one fraction analogous to said "natural gasoline"; and returning a portion of said "latter" fraction to the dissolving step.

7. The method of extracting petroleum bearing solid material which comprises dissolving a portion of the petroleum by contacting said petroleum bearing solid material with "butane" delivered and applied to said petroleum bearing solid material while maintained in the liquid phase, maintaining said "butane" in the liquid phase while in contact with said petroleum bearing solid material; withdrawing the solution; then subjecting the solution, while it still contains a substantial amount of butane, to the action of heat at such temperature that pyrolytic reactions take place; then separating the solution into fractions, including one fraction of "butane"; and returning a portion of said "butane" fraction to the dissolving step.

8. The method of extracting petroleum bearing solid material which comprises dissolving a portion of the petroleum by contacting said petroleum bearing solid material with "propane" delivered and applied to said petroleum bearing solid material while maintained in the liquid phase, maintaining said "propane" in the liquid phase while in contact with said petroleum bearing solid material; withdrawing the solution; then subjecting the solution, while it still contains a substantial amount of said "propane", to the action of heat at such temperature that pyrolytic reactions take place; then separating the solution into fractions including one fraction of "propane"; and returning a portion of said "propane" fraction to the dissolving step.

HENRY ROSENTHAL.
